UNITED STATES PATENT OFFICE.

JOSEPH C. SHUTTLEWORTH, OF BROOKLYN, NEW YORK.

WINDOW VENTILATOR.

Application filed June 3, 1921. Serial No. 474,605.

To all whom it may concern:

Be it known that I, JOSEPH C. SHUTTLEWORTH, a citizen of the United States, and a resident of the city of New York, borough 5 of Brooklyn, in the county of Kings and State of New York, have invented a new and Improved Window Ventilator, of which the following is a full, clear, and exact description.

10 This invention relates to window ventilators and has for an object to provide an improved construction which may be bodily applied and removed at any time and may be arranged at the top or bottom of any 15 window within certain limits.

Another object in view is to provide a ventilator having a number of ventilating openings and sliding end members for adapting the ventilator to windows of different sizes.

20 A further object of the invention is to provide a ventilator with spaced protecting screens and associated members for presenting disinfectant receiving chambers in addition to providing openings for the passage 25 of air.

In the accompanying drawing—

Figure 1 is a fragmentary front view of a window frame and part of a window sash 30 together with a view of the invention applied, certain parts being broken away.

Figure 2 is a sectional view through Figure 1 on line 2—2, the same being on an enlarged scale.

35 Figure 3 is an enlarged fragmentary sectional view through Figure 1 on line 3—3.

Figure 4 is a perspective view of the ventilator in a folded position.

Referring to the accompanying drawing 40 by numerals, 1 indicates a window case of any kind and 2 a sliding sash. The ventilator 3 is adapted to be placed on top of the sash 2 and the sash moved upwardly until the ventilator engages the upper part of 45 the window frame 1. If desired, the ventilator 3 can be arranged at the bottom of the window frame without departing from the spirit of the invention.

In forming the ventilator 3, it is preferably formed into sections 4 and 5 hinged together at 6 by a suitable hinge whereby it may be folded as shown in Figure 4 for storage or disposal in any desired manner. In order that the ventilator may properly 55 fit windows of slightly different sizes, sliding plates 7 and 8 are provided. As both

of these plates and associated members are identical, the description of one will apply to both. As shown in Figures 1 and 3 the plate 8 is provided with grooves 9 adapted 60 to receive the projecting guiding keys 10 while at the same time the plate 8 is guided by pins 11 which pins are fitted into the plate and slidably fit into guiding tubes 12 and 13. Preferably, the plate 8 is cut away 65 at 14 so as to expose the opening 15 and at the same time allow a comparatively long bearing surface by reason of the projection 16. A suitable spring 17 is arranged on each of the pins 11 for resiliently holding 70 the plate 8 in its outer position and against the frame 1.

In forming the section 5, for instance, inner and outer boards 18 and 19 are provided, said boards being provided with suitable 75 openings 15. A separate sheet 20 of wire mesh is stretched over each of the boards so as to cover these openings as shown in Figure 3 and provide a space between the wire mesh which is divided by partitions 21 in 80 order to present compartments 22 in which a suitable disinfectant 23 may be placed. In order to space the boards 18 and 19 apart, spacing strips 24 are arranged between the boards and held in place by screws, nails or 85 other suitable means. Preferably, the boards 18 and 19 are held in place by screws or other easily removable securing means whereby new disinfectant 23 may be placed in any of the compartments 22 with little 90 trouble. If desired, metallic trimming rings 25 may be arranged in the various openings 15 to produce a pleasing appearance to the device.

What I claim is:—

1. A ventilator of the character described comprising a body formed with a front and back board, each of said boards having aligning openings, a spacing strip between said boards along one end and the sides 100 thereof, partition members between said boards extending from one side strip to the other, a wire mesh arranged between said boards and at each side of said strips, said wire mesh covering said openings, a plate 105 arranged to slide in the open end of said body, said plate being formed with longitudinal grooves, and a member secured to one of said boards adjacent the open end of the body and fitting in one of said grooves. 110

2. In a ventilator of the class described, a pair of hinged ventilating sections each com-

prising a rear and a front board, a spacing strip between said boards at the edges thereof and extended from a point intermediate one end and the center, around one end, over the opposite end between the first mentioned end and the center of the board, a plurality of partition members extending transverse to the longitudinal axis of said body and forming between the boards a plurality of compartments, each compartment

having an opening, a tubular member secured to two of said partition members, a rod extending through said tube, a plate slidably held between said boards, said rod being secured to said plate, a spring surrounding said rod between said tube and said plate, and means secured to one of said boards for preventing the lateral movement of said plate.

JOSEPH C. SHUTTLEWORTH.
